Inventor:

Thos. W. Bishop

United States Patent Office.

THOMAS W. BISHOP, OF AUSTIN, INDIANA.

Letters Patent No. 70,396, dated November 5, 1867.

IMPROVEMENT IN CORN-SHELLERS.

The Schedule referred to in these Letters Patent and making part of the same.

TO ALL WHOM IT MAY CONCERN:

Be it known that I, THOMAS W. BISHOP, of Austin, in the county of Scott, and State of Indiana, have invented a new and useful Corn-Sheller; and I do hereby declare the following to be a full, clear, and exact description of the same, reference being had to the accompanying drawings, which are made a part of this specification.

Figure 1 is a plan of my improved corn-sheller.

Figure 2 is a front elevation thereof, a portion of the front of the casing being broken away to expose the shelling device proper.

Figure 3 is a vertical section on the line $z z$.

Figure 4 is a detached perspective view, showing the mode of supporting the wheel which carries the shelling device.

Similar letters of reference indicate corresponding parts in the several figures.

The subject of this invention is a corn-sheller having two rotary spring-controlled jaws or plates, which are provided on their inner opposing surfaces with helical ribs or threads, which conjunctively form an inside screw, and which are also provided with angular projections, which serve to detach the corn from the ear as the latter is fed between the jaws by the screw.

In the drawings, A represents a metallic supporting frame, to which is screwed or otherwise united the casing B, which encloses the corn-shelling device. The upper portion of the frame A forms a bearing for the vertical arbor or spindle C' of the bevel-wheel C. This wheel gears with a similar bevel-wheel, D, which has a central opening, D², of sufficient size to permit the passage through the wheel of the largest corn-cobs. The hub or neck D¹ of the wheel D is journaled in the rear wall of the casing B, as shown in fig. 4. E E are two corresponding jaws or plates, which are cast so as to bulge in the middle, and leave an intervening opening when brought together. These jaws are cast with flanges E' E', whereby they are secured to the front or face of the hub D¹ by means of screws e³. The slots e in the flanges E', which accommodate the screws e³, enable the jaws to move freely away from and toward each other on the hub D¹. The jaws E E are forced toward each other by springs F encircling guide-rods G, there being in the illustration four springs and two guide-rods, which latter pass through the abutting ends of the jaws E E. e² e² are sharp-edged oblique projections, formed on the outer edges of the respective jaws E E. e¹ e¹ are helical ribs formed on the inner or opposing faces of the jaws E E, and forming conjunctively a female screw or feeder. The supporting frame A may be screwed or otherwise attached to a board, stand, table, or other rest by its feet A'. The wheel C is turned by a handle, F², and imparts a rotary motion to the wheel D and jaws E E.

The ear of corn is introduced through an opening, B', in the front wall of the casing B, and the nose or point of the ear is inserted between the jaws E E. The ear is held against rotation by hand, and as the jaws rotate the projections e² wedge themselves between the grains, and rapidly separate the latter from the cob. The shelled corn falls through the opening at the bottom of the casing B, and may be caught in a suitable receptacle, while the naked cob is fed between the jaws by the screw e¹, its protruding end being caught by hand and held behind the wheel D till completely shelled and ejected from the jaws. The springs F permit the jaws E E to expand and contract, so that they will receive, embrace, and act with equal effect upon ears of different size. When the corn has grown over the end of a cob, the grains are removed from the end or nose by giving it a twist in the serrated opening G. This fits the ear for the more perfect and complete action of the jaws.

Having described my invention, the following is what I claim as new, and desire to secure by Letters Patent:

1. I claim the combination with the shelling device E E of the gear-wheels C and D, hub D¹, and central opening D²; substantially as and for the purpose set forth.
2. I claim the serrated opening G, substantially as and for the purpose described.
